DES. 2154

Nicholas S. Wedder, of Troy, N.Y.

Assignor to

Geo. Church and Geo. Troy, N.Y.

Letters Patent No. 2154. Dated Aug. 1. 1865.

Design for a Stove Base.

The schedule referred to in these Letters Patent and making part of the same.

To all whom it may concern:—

Be it known that I, Nicholas S. Wedder, of the City of Troy, in the County of Rensselaer, and State of New York, have originated and produced a new Design for a base of a stove, of which the following is a full, clear and exact description, reference being had to the accompanying photograph of a stove base having my said design. My new design is distinguished from all others by having an inner, elevated, annular, convex moulding A, ornamented by a series of columns B, connected by arches C, and surrounded by a lower concave moulding D, which is ornamented by a series of rosettes E, and surrounded by a compound border moulding F, having a series of outwardly-projecting ornaments G: all shaped and arranged together so as to present an appearance like that represented by the aforesaid photograph.

What I claim as my invention and desire to secure by Letters Patent is the design for a base of a stove herein set forth.

Witnesses:—
